UNITED STATES PATENT OFFICE.

PETER H. JACKSON, OF NEW YORK, N. Y.

DESIGN FOR A LAMP-POST.

Specification forming part of Design No. 6,348, dated January 21, 1873.

To all whom it may concern:

Be it known that I, PETER H. JACKSON, of New York city, in the State of New York, have invented a Design for Lamp-Post, of which the following is a specification:

My design may be termed paneled Florentine. Its nature is fully represented in the accompanying photographic illustration, to which reference is made.

A represents the lower and thicker portion of the post, paneled, as indicated by *a*. B is a swelled or beaded portion with a torus tastefully wrought with what is sometimes termed egg and dart. C is a band or collar formed of acanthus leaves, from which rises a fluted shaft, D, surrounded by a tastefully-swelled portion, E. The cross-bar F is wrought with what may

be termed lily prolonged. The bottom of the part A is flared and beaded.

The details of the ornaments may be varied in some degree. The depth of the depressions and the heights of the elevations may be increased or diminished. Colors may be applied to bring out the decorative features more prominently, particularly in fronts of theaters and other places where varieties of colors may be deemed appropriate.

What I claim as my invention is—

The within-described paneled Florentine design for lamp-post.

PETER H. JACKSON.
